Atty's

UNITED STATES PATENT OFFICE.

BURT A. PETERSON, OF ROCKFORD, ILLINOIS, ASSIGNOR, BY MESNE ASSIGNMENTS, TO BARBER-COLMAN COMPANY, OF ROCKFORD, ILLINOIS, A CORPORATION OF ILLINOIS.

MEANS FOR LOCKING YARN CARRIERS UPON THEIR SUPPORTS.

Application filed September 14, 1921. Serial No. 500,528.

To all whom it may concern:

Be it known that I, BURT A. PETERSON, a citizen of the United States, residing at Rockford, in the county of Winnebago and 5 State of Illinois, have invented certain new and useful Improvements in Means for Locking Yarn Carriers upon Their Supports, of which the following is a specification.

This invention relates particularly to improvements upon the construction shown in the Colman Patent No. 1,329,504, dated February 3, 1920. The advantages derived from the invention will be apparent as the description proceeds.

15 In the accompanying drawing, Figure 1 is a longitudinal central sectional view. Fig. 2 is a fragmental side view of the cheese arm.

The form of yarn carrier herein shown 20 is identical with that shown in the co-pending application of Howard D. Colman filed September 14, 1921, Ser. No. 500,512. The yarn carrier comprises a tubular section A adapted to fit upon a suitable spindle or 25 pivot and a rotatable section B upon which a yarn mass may be built.

The support upon which the yarn carrier is mounted may be of any suitable character, 30 that herein shown comprising an arm 1 having an outer end portion 2 of generally circular form. In the end portion 2 is a circular depression 3. A spindle 4 is fixed to the arm 1 at the center of the depression. Surrounding the base of the spindle and seated in the depression 3, is a sheet-metal 35 housing 5 having a peripheral wall 6 and an end wall 7. The end wall 7 has an opening 8 through which the spindle 4 projects. The housing 5 is held tightly against the bottom 40 of the depression 3 by means of a split ring 9 fitting within an annular groove 10 in the spindle and bearing against the end wall 7.

Two diametrically opposite openings 11 are formed in the periphery of the housing 45 6. Two latch elements in the form of balls 12 extend partially through these openings, the balls being pressed outwardly by a curved leaf spring 13 having sockets 14 for the balls.

50 On the inner end of the section A of the

yarn carrier is a diaphragm 15, to the periphery of which is secured a flange or ring 16. The ring 16 has an inturned annular flange 17 adapted to be engaged by the balls 12.

In use, the operator mounts the yarn carrier on the cheese arm 1 by slipping the tube A upon the spindle 4 until the flange 17 has passed the balls 12. The parts are so proportioned that the pressure of the balls 60 against the flange 17 holds the diaphragm 15 against the end wall 7. The yarn carrier is thus held in a definite invariable position upon the cheese arm.

When the formation of the cheese has been 65 completed, the operator pulls the cheese off the spindle, the spring 13 yielding to permit the flange 17 to pass the balls 12.

When any of the parts need repair or replacement, the split ring 9 is removed, whereupon the housing 5 may be slid off the spindle 4, and the balls 12 and spring 13 removed from the housing.

It will be apparent that the means for locking the yarn carrier upon its support is 75 very simple and therefore inexpensive to manufacture, that the moving elements are not subject to rapid wear or very liable to accidental injury, and that repairs may be easily and cheaply made when required. 80

I claim as my invention:

1. The combination of an arm having a circular depression at its outer end, a spindle rigidly secured to the arm centrally of the depression, a sheet-metal housing having a 85 peripheral wall and an end wall, said end wall having an opening through which the spindle projects, the spindle having an annular groove, a split ring seated in the groove and bearing against said end wall to hold the housing against the bottom of the depression, said housing having two diametrically opposite openings in its peripheral wall, balls projecting partially through said openings, a curved leaf spring having sockets 90 to receive said balls, and a yarn carrier adapted to be mounted upon the spindle and having an annular member surrounding the housing and arranged to be engaged by the 95 balls.

2. The combination of an arm having a circular depression at its outer end, a spindle rigidly secured to the arm centrally of the depression, a sheet-metal housing having a 65
5 peripheral wall and an end wall, said end wall having an opening through which the spindle projects, means to hold the housing against the bottom of the depression, said housing having an opening in its peripheral 70
10 wall, a ball projecting partially through said opening, a spring behind said ball, and a yarn carrier adapted to be mounted upon the spindle and having an annular member surrounding the housing and arranged to be 75
15 engaged by the ball.
3. The combination of an arm having a circular depression at its outer end, a spindle rigidly secured to the arm centrally of the depression, a sheet metal housing having a per 80
20 ipherial wall and an end wall, said end wall having an opening through which the spindle projects, means to hold the housing against the bottom of the depression, said housing having two diametrically opposite openings 85
25 in its peripheral wall, balls projecting partially through said openings, spring means behind the balls, and a yarn carrier adapted to be mounted upon the spindle and having an annular member surrounding the housing 90
30 and arranged to be engaged by the balls.
4. The combination of an arm, a spindle rigidly secured to the arm, a housing surrounding the lower portion of the spindle, said housing having an opening, a ball projecting partially through said opening, a spring behind said ball, and a yarn carrier 95
35 adapted to be mounted upon the spindle and having an annular member surrounding the housing and arranged to be engaged by the ball.
5. The combination of an arm, a spindle rigidly secured to the arm, a sheet-metal housing having a peripheral wall and an end wall, said end wall having an opening 100
45 through which the spindle projects, means to hold the housing in place, said housing having two diametrically opposite openings in its peripheral wall, balls projecting partially through said openings, a curved leaf 105
50 spring having sockets to receive said balls, and a yarn carrier adapted to be mounted upon the spindle and having an annular member surrounding the housing and arranged to be engaged by the latch element.
6. The combination of an arm, a spindle rigidly secured to the arm, a sheet-metal housing having a peripheral wall and an end wall, said end wall having an opening through which the spindle projects, means to 110
55 hold the housing in place, a locking element carried by the housing, and a yarn carrier adapted to be mounted upon the spindle and having a locking member to coact with first- 115
60 mentioned locking element.
7. The combination of an arm, a spindle rigidly secured to the arm, a stationary housing surrounding the base of the spindle, a locking element carried by the housing, and a yarn carrier adapted to be mounted upon the spindle and having a locking element projecting beyond one end of the yarn carrier and arranged to coact with the first- 120
65 mentioned locking element.
8. An arm having a spindle attached thereto, a part adjacent to the spindle, said part having an opening therein, a ball projecting partially through the opening, a spring normally holding the ball in such position, and a yarn carrier adapted to be mounted upon the spindle and having an annular member adapted to be engaged by the ball to lock the yarn carrier on the spindle.
9. An arm having a spindle attached thereto, a part adjacent to the base of the spindle, said part having an opening therein, a locking element projecting partially through the opening, a spring normally holding the locking element in such position, and a yarn carrier adapted to be mounted upon the spindle and having an annular member adapted to be engaged by the locking element to lock the yarn carrier on the spindle.
10. The combination of an arm having a circular depression at its outer end, a spindle rigidly secured to the arm centrally of the depression, a housing at the bottom of said depression, said housing having a peripheral wall and an end wall, said end wall having an opening through which the spindle projects, said housing having an opening in its peripheral wall, a spring-actuated latch element projecting partially through said opening, and a yarn carrier 125
70 adapted to be mounted upon the spindle and having an annular member surrounding the housing and arranged to be engaged by the latch element.
11. The combination of an arm, a spindle rigidly secured to the arm, a housing surrounding the lower portion of the spindle, said housing having an opening, a spring-actuated latch element projecting partially through said opening, and a yarn carrier 130
75 adapted to be mounted upon the spindle and having an annular member surrounding the housing and arranged to be engaged by the latch element, the latter serving to hold the yarn carrier against the housing.
12. The combination of an arm, a spindle rigidly secured to the arm, a housing adjacent to said arm, said housing having a peripheral wall and an end wall, said end wall having an opening through which the spindle projects, a locking element partially enclosed by the housing, and a yarn carrier 135
80 adapted to be mounted upon the spindle and

having a locking member to coact with the first-mentioned locking element.

13. An arm having a spindle attached thereto, a spring-actuated locking element adjacent to the base of the spindle, and a yarn carrier adapted to be mounted upon the spindle and having an annular member pro-

jecting beyond one end of the yarn carrier and adapted to be engaged by the locking element to lock the yarn carrier on the 10 spindle.

In testimony whereof, I have hereunto set my hand.

BURT A. PETERSON.
